CLAIM

The ornamental design for a liquid soap dispenser carton, as shown and described.

DESCRIPTION

FIG. 1 is a top right perspective view of a liquid soap dispenser carton showing the new design;

FIG. 2 is a top plan view thereof;

FIG. 3 is a front plan view thereof;

FIG. 4 is a rear plan view thereof;

FIG. 5 is a right side plan view thereof;

FIG. 6 is a left side plan view thereof;

FIG. 7 is a bottom plan view thereof;

FIG. 8 is a cross sectional view of the liquid soap dispenser carton, taken along lines 8-8 of FIG. 3; and,

FIG. 9 is a bottom left perspective view of our liquid soap dispenser carton design. The broken lines depict portions of the article that form no part of the claimed design.
